CLAIM

The ornamental design for a combined article holder and cigarette snuffer, as shown and described.

DESCRIPTION

FIG. 1 is a perspective view of the combined article holder and cigarette snuffer showing my new design;

FIG. 2 is a front elevational view thereof;

FIG. 3 is a rear elevational view thereof;

FIG. 4 is a side elevational view of the left side of FIG. 1;

FIG. 5 is a side elevational view of the right side of FIG. 1;

FIG. 6 is a top plan view thereof; and,

FIG. 7 is a bottom plan view thereof.

The combined article holder and cigarette snuffer is characterized with a blind cylindrical bore extended downwardly from the top of a case adapted to accommodate a cylindrical object, such as a cigarette, pen or pencil. A downwardly directed linear clip is joined to an upper portion of the case.
